UNITED STATES PATENT OFFICE.

CHARLES R. KEERAN, OF CHICAGO, ILLINOIS.

JAR CLOSURE.

1,425,594.

Specification of Letters Patent. Patented Aug. 15, 1922.

Application filed October 27, 1917. Serial No. 198,808.

To all whom it may concern:

Be it known that I, CHARLES R. KEERAN, a citizen of the United States, residing at Chicago, county of Cook, and State of Illinois, have invented certain new and useful Improvements in Jar Closures, of which the following is a specification.

The present invention has to do with improvements in closures for vacuum preserving jars and the like, such as are used for preserving fruits and food products. In the use of these jars, the exterior atmospheric pressure resulting from a partial vacuum within the receptacle serves to hold the cover or closure in place. The pressure thus exerted will, of course, depend upon the degree of perfection through which the vacuum is established, and also the extent or area of the surface of the cover which is acted upon by the air pressure. If it be assumed that an air pressure of twelve pounds per square inch is established, and that the area of the cover acted upon by this pressure amounts to six and one-fourth square inches, the pressure or force exerted on the cover resulting from the partial vacuum within the jar will amount to seventy-five pounds. This is, of course, a very considerable item, and it will readily be appreciated that the cover cannot be easily removed without breaking the vacuum. Ordinarily there is used as part of the closure a gasket of rubber or suitable compressible material which is interposed between the cover and the edge of the jar or receptacle. By introducing a knife or other suitable instrument between the cover and the gasket, an opening can be produced through which the air will enter the jar, thereby breaking the vacuum.

While it is theoretically a simple matter to relieve the vacuum in the manner just explained, it becomes a more difficult operation in practice by reason of the fact that it is quite desirable, and in many cases necessary, to provide a flange either on the cover or in conjunction therewith, which flange encircles and encloses the gasket to a greater or less extent, thereby preventing the introduction of a knife blade or other instrument in the manner above explained, so long as the flange remains in the way.

One of the objects of the present invention is to so construct the closure in those cases where a flange is used, either on the cover or in conjunction therewith, that the knife or other object may be conveniently

introduced between the cover and the gasket in such a manner as to effectively break the vacuum and permit the cover to be removed.

In Letters Patent No. 1,226,532, issued to me May 15, 1917, for improvements in receptacle closures, I have disclosed, in conjunction with other parts a peripheral flange whose function and purposes are, to a greater or less extent, to encircle the gasket and center and protect the same while the closure is being applied to the jar. I have discovered the fact that the closure may be more securely assembled if a flange be employed which is provided with indentations, distortions, or irregularities capable of engaging with the parts of the closure in such a manner as to maintain them in assembled relation. By such means the parts are prevented from sparing or getting disarranged while being applied operatively upon the jar, preparatory to putting on the screw ring.

Other objects and uses of the invention will appear from a detailed description of the same which consists in the features of construction and combinations of parts hereinafter described and claimed.

Referring to the drawing:

Figure 1 is a perspective view of the upper portion of a preserving jar having applied thereto a closure embodying the features of the present invention, the screw ring being removed;

Fig. 2 is a fragmentary enlarged cross section through the parts shown in Fig. 1, the screw ring in this figure being applied to the jar;

Fig. 3 is a view corresponding to Fig. 1 with the exception that the flange for the disk is formed separately therefrom and is provided with indentations or the like for assisting in holding the disk in place;

Fig. 4 is a view corresponding to Fig. 2 relating, however, to the modified arrangement of Fig. 3; and

Fig. 5 is a view corresponding to Fig. 2 showing a still further modified construction.

In each of the several figures the neck of the jar or other receptacle is designated by the numeral 6. As a matter of convenience the same is shown as being provided with theads 7 whereby a screw ring 8 may be threaded onto the upper portion of the jar, in case that may be desirable.

In the arrangement shown in Figs. 1 and

2, the closure makes use of a sealing cover in the form of a disk designated by the numeral 9. This disk which is made of any suitable material is of circular shape, and 5 is provided around its edges with a downwardly depending flange 10. Preferably the disk, as shown in Fig. 1, is made of thin sheet metal, such, for instance, as aluminum. In the modified form of Figs. 3, 4, 10 and 5, which will be hereinafter described in detail, the disk may conveniently be made of glass or porcelain, as well as of sheet metal. I prefer to provide on the upper surface of the disk an annular rib or bead 11, in the 15 manner clearly shown in Figs. 2, 4, and 5, the purpose of which will presently be explained.

Interposed between the disk and the upper edge of the jar neck is a gasket 12 of 20 rubber or other suitable material. This gasket is placed interiorly of the flange 10 before the disk 9 is applied to the jar. The gasket may be made a trifle over-size so that when forced into place inside the flange 25 10 of the disk it will not become displaced when the disk is being handled preparatory to sealing the receptacle. In order to facilitate the application of the disk a screw ring 8 may be employed, either temporarily or 30 permanently, to force the edge or peripheral portion of the disk down tightly upon the gasket 12. The screw ring may be provided with the usual threads 13 to engage with the threads 7 on the upper portion of the 35 receptacle and be formed also with an open central portion bounded by a peripheral edge 14. When the closure has been applied in the manner described, the parts will be related somewhat as shown in Fig. 2. The 40 annular rib 11 of the disk which is arranged to fit within the peripheral edge 14 of the screw ring serves to center the disk with respect to the ring and jar, so that when the ring is screwed tightly upon the receptacle 45 the disk will be properly positioned for sealing the jar, irrespective of whether or not the flange 10 extends down sufficiently to fit around the upper edge of the jar. When the peripheral portion 15 of the screw ring 50 bears down upon the disk, it makes a seal between the disk and the receptacle through the medium of the gasket 12. If the contents of the jar are comparatively hot when the seal is formed as hereinabove described, 55 a partial vacuum will be formed within the receptacle as its contents cool. The atmospheric pressure resulting from the partial vacuum that ensues within the receptacle will be sufficient to hold the disk in place 60 without the aid of the screw ring. When this stage of the sealing operation has been reached the screw ring may be removed, if desired, and the jar, as shown in Figs. 1 and 3 may then be set away minus this 65 part. This results in a very material sav-

ing to the user, as, for example, a dozen jars of fruit may be put up daily with the use of but twelve screw rings for the entire season. This is accomplished by removing the screw rings which had been applied to 70 jars sealed the preceding day.

After the vacuum has been established, it can be easily broken by inserting a knife or other proper instrument between the gasket 12 and the peripheral portion 15 of 75 the disk. In order to facilitate such a procedure, I have provided one or more slits or openings 16 in or adjacent the flange 10 permitting the knife or other implement used to be readily inserted therethrough, 80 and worked in between the peripheral portion 15 of the disk and the sealing gasket so as to break the vacuum without destruction of the disk. The screw ring 8 should, of course, be removed before any effort is 85 made to insert the implement for the purpose of breaking the vacuum.

The arrangement shown in Figs. 3 and 4 is similar to that already explained, with the exception that the flange 10 is formed 90 independently of the disk. In this construction the flange designated as 17 in Figs. 3 and 4 is formed as part of a guide ring 18 which is arranged to overlie the peripheral portion of the disk so as to facilitate the 95 application of the parts to the jar. It is to be observed that this flanged portion 17 of the guide ring 18 is provided with a slit or slot 19, and to this extent corresponds to the flange 10 of the arrangement of Figs. 100 1 and 2. The essential point is that the slits or slots are provided in the flange, regardless of whether the said flange be formed on or independently of the disk which serves to cover the receptacle mouth. 105

It is to be observed that the flange 17 in the arrangement shown in Figs. 3 and 4 is provided with one or more indentations or the like 20 capable of engaging with the disk 9 to hold the same in proper assembly 110 relation during the process of applying the closure to the jar or receptacle. While I have shown the indentations 20 only on the arrangement of Figs. 3 and 4, it is very evident that they may be also used in the 115 construction of Figs. 1 and 2, if desired. Further, the indentations and the slits or slots can be used either together or separately as desired in any given case.

To facilitate assembly of the closure, as 120 shown in Figs. 3 and 4, the guide ring 18 may be placed on a flat surface, such as a table, with its flared edge upward, permitting the disk to be inserted into position by forcing the same past the indentations 125 20. The guide ring with the disk secured in place may then be picked up and handled as a unit. The gasket 12 may be attached to the disk 9, but if not it is then inserted in any convenient manner. In case the

gasket 12 is not attached to the disk 9, it will probably be found desirable to form the gasket a trifle over-size, so that it will fit snugly within the guide ring 18 to prevent its dropping out when the cap is handled or turned over. When assembled, the three parts, guide ring, disk, and gasket, become a unit which may be applied as one piece to the jar.

10 In the arrangement of Fig. 5, I have shown a disk 21 somewhat thicker than those illustrated in Figs. 2 and 4, such as may be conveniently formed of porcelain or glass, although the metallic disk of Fig. 1 made 15 with a short flange would work as well. This disk is arranged to fit within the screw ring 8 which is formed similar to the corresponding parts illustrated in Figs. 2 and 4, with the exception that it is provided with 20 an inwardly extending indentation or protuberance 22. In assembling the parts of the closure of Fig. 5, the disk 21 is snapped by the indentations 22 into its final position and there held in place by such indentations. The gasket 12 which occupies a position 25 interiorly of the screw ring may be made a trifle oversize to better hold itself in place, or, if preferred, may be adhered to the disk. The closure just described obviously has its component parts retained in 30 assembled relation by the means pointed out, so that it may be handled and applied to the jar as a unit.

It will be apparent from the description of my invention and the several figures of the drawing, that the several devices which I have disclosed contain numerous features tending to facilitate the application of the closure to the jar; that these features may be used separately or in combination, as 35 may be found desirable; that the closure provided by the means described will be effective to preserve the contents of the jar for an indefinite period; and that the breaking of the seal may be accomplished in a simple 40 manner without the necessity of mutilating or destroying the disk, thereby rendering it 45 possible to reuse it many times.

I claim:

A closure for a jar, comprising in combination a disk arranged to cover the jar mouth and provided with a depending flange adapted to lie adjacent the jar neck, a gasket adapted for interposition between the disk and jar mouth, there being a slit formed in 50 the flange adjacent the under face of the disk, whereby a wedging implement may be inserted to open up a passage between the disk and gasket, and means co-operating with the jar neck for clamping the disk and 55 gasket operatively upon the jar mouth, substantially as described.

CHARLES R. KEERAN.
